CURTAIN STRETCHER

Walter W. Block, Kenosha, Wis.

Application August 14, 1940, Serial No. 352,485

3 Claims. (Cl. 287—99)

This invention relates to curtain stretchers and more particularly to the hinges of the horizontal rails of foldable type of curtain stretchers. Some curtain stretchers are made so that when not in use they may be completely taken apart into the various elements and stored whereas another type of curtain stretcher known as the foldable type is constructed so that only a few component parts of the stretcher need be removed therefrom and the remaining parts may be folded to provide a compact knocked-down structure which may be easily stored and which may also be readily set up into operative position when desired. The main component parts of an ordinary curtain stretcher comprise the horizontal rails and vertical posts and in a foldable curtain stretcher the horizontal rails may be provided with hinges at or near their medial point so that one-half of each rail may be folded back upon the other one-half. In many curtain stretchers a vertical post is employed at or near the center hinge of the horizontal rails. In order to fold the horizontal rails it is necessary or desirable to remove the vertical post which is arranged at this position. This vertical post is generally secured to the horizontal rails by a clamp device or by a bolt and wing nut connection. This connecting device is generally in the way after the vertical post is removed and when folding the horizontal rails into folding position. It is a primary object of my invention to provide a hinge which will enable folding of the horizontal rails at or near the medial point without in any way interfering with the connecting device at this point.

A connecting device often employed is a bolt and wing nut and in curtain stretchers heretofore constructed it has often been necessary to completely remove the wing nut and bolt in order to effect a folding of the horizontal rails. Such removal of the bolt and wing nut often results in the loss or misplacement of these parts and in any event the reassembling of the parts is rendered difficult.

A further object is to provide a center hinge for the horizontal rails of the curtain stretcher which will not necessitate the removal of the bolt and wing nut used for securing a vertical post to the horizontal rails at the hinge point. It is often desirable to reduce the size of a curtain stretcher for temporary storage when it is inconvenient to take the stretcher apart completely for a compact and more or less permanent storage. When such temporary storage is desired a housewife or other user of stretchers wants to

have the stretcher available for ready use and it is a still further object of my invention to provide hinges for the horizontal rails of a curtain stretcher so that it can be speedily, simply and with a minimum amount of trouble folded on a vertical axis one-half back against the other one-half.

Other and further objects of the present invention will be apparent from the following description and claims and are illustrated in the accompanying drawings which, by way of illustration, show a preferred embodiment and the principle thereof and what I now consider to be the best mode in which I have contemplated applying that principle. Other embodiments of the invention embodying the same or equivalent principle may be used and structural changes may be made as desired by those skilled in the art without departing from the present invention and the scope of the appended claims.

In the drawings

Fig. 1 is a front elevation of a portion of a curtain stretcher embodying my invention;

Fig. 2 is a sectional view taken on the line 2—2 of Fig. 1;

Fig. 3 is a detail view taken on the line 3—3 of Fig. 2;

Fig. 4 is a detail view taken on the line 4—4 of Fig. 1;

Fig. 5 is a view similar to Fig. 4 but showing the rail in folded position and showing the vertical post removed;

Fig. 6 is a perspective view similar to Fig. 3 showing the vertical post removed; and

Fig. 7 is a perspective view similar to Fig. 6 but showing the rail in folded position.

A curtain stretcher generally indicated by 8 comprises a top horizontal rail 9 and a bottom horizontal rail 10 interconnected by a center vertical post 11. The rail 9 is divided into two sections 12 and 13 secured together by a hinge 14. The hinge comprises two members 15 and 16. The member 15 is secured to section 13 of the rail 9 by any suitable means such as the rivets 17 and the member 16 is secured to the section 12 of the rail 9 by similar devices such as rivets 18. The member 15 extends beyond the section 13 and overlaps the section 12 and the member 16. A portion 19 of the member 15 is pressed upwardly forming shoulders at 20 and 21 to accommodate that part of the member 16 lying on top of the section 12. The portion 19 is extended at 22 and the overlying part of the member 16 is similarly and co-extensively extended at 23 sideways from the rail 9. The ex-

tensions 22 and 23 are provided with aligned openings therethrough to receive a pintle 24 pivotally securing the hinge members together. The member 15 is cut away at 25 to receive the side portion of the member 16 which member extends slightly beyond the end of the section 12 and slightly overlaps the end of the section 13. A bolt 26 extends through and beyond the section 12 and the side portion of the member 16 is provided with a suitable nut such as the wing nut 27. The threads on the outer end of the bolt may be upset to prevent accidental removal of the nut from the bolt. The cut away portion 25 of the member 15 is notched at 28 so when the sections of the rail are folded about the pintle 24 the free end of the bolt and the nut 27 will pass through the openings provided by the cut away portions 25 and 28 into the position shown in Fig. 7 leaving the nut and bolt secure to the section 12.

A vertical post 11 is slotted at 29 to receive the bolt 26 whereupon the nut 27 may be tightened to secure the post 11 to the rail 9 as best shown in Figs. 3 and 4.

A hinge generally indicated by 30 may be of the same structure as the hinge 14 heretofore described but arranged in upside down relation and it may be preferable in this instance to use a different kind of clamping device for securing the vertical post 11 to the rail 10. Such a clamping device is indicated by 31, Figs. 1 and 2 and which does not embody a bolt extending through the rail 10 but it is possible to provide a vertical post of the conventional type having a slot therein and having the same type of bolt as the bolt 26 extending through the slot of the vertical post and through the rail 10 just as the bolt extends through the rail 9. The only difference between the structure and associated parts of the upper rail and the lower rail is that the lower rail should be adjustable vertically and such adjustment is provided by the clamp device shown in Figs. 1 and 2 or by the conventional slot arrangement heretofore referred to.

While I have illustrated and described a selected embodiment of my invention it is to be understood that this is capable of variation and modification and I therefore do not wish to be limited to the precise details set forth but desire to avail myself of such changes and alterations as fall within the scope of the following claims:

I claim:

1. In a curtain stretcher, a rail comprising a pair of sections adapted for arrangement in end

to end relation, a post, a hinge comprising a pair of members each rigidly secured to one of said sections at the abutting ends thereof, a pintle securing said members together in pivotal relation, one of said members extending beyond the section to which it is secured and overlapping the other of said members and the end portion of the other of said sections, said one member being cut away to receive a portion of said other member, and means mounted in the end portion of the section to which said other member is secured and projecting through said cut away portion for removably securing said post to said rail, whereby said hinge may be operated to fold said sections one upon another without removal of said post securing means.

2. In a curtain stretcher, a rail comprising a pair of sections adapted for arrangement in end to end relation, a post, a hinge comprising a pair of members each rigidly secured to one of said sections at the abutting ends thereof, a pintle securing said members together in pivotal relation, one of said members extending beyond the section to which it is secured and overlapping the other of said members and the end portion of the other of said sections, said one member being cut away to receive a portion of said other member, a bolt projecting through the end portion of the section to which said other member is secured and through said portion of said other member, a nut on said bolt for removably securing said post to said rail to render said hinge inoperative to fold said sections, whereby upon removing said post said hinge may be operated without removing said nut from said bolt.

3. In a curtain stretcher, a rail comprising a pair of sections adapted for arrangement in end to end relation, a post, a hinge comprising a pair of members each rigidly secured to one of said sections at the abutting ends thereof, a pintle securing said members together in pivotal relation, one of said members extending beyond the section to which it is secured and overlapping the other of said members and the end portion of the other of said sections, said one member being cut away to receive a portion of said other member, a bolt projecting through the end portion of the section to which said other member is secured and through said portion of said other member, a nut irremovably held on said bolt for removably securing said post to said rail to render said hinge inoperative to fold said sections, whereby upon removing said post said hinge may be operated without removing said bolt and nut.

WALTER W. BLOCK.
